United States Patent Office

Des. 221,358
Patented Aug. 3, 1971

221,358

TYPEWRITER

Donald M. Genaro, Haworth, N.J., assignor to Sperry Rand Corporation, New York, N.Y.

Filed Sept. 3, 1969, Ser. No. 18,991

Term of patent 14 years

Int. Cl. D18—01

U.S. Cl. D64—11

FIG. 1.

FIG. 2.

FIG. 3.

FIG. 4.

FIG. 5.

FIG. 1 is a front perspective view of a typewriter showing the new design;

FIG. 2 is a right elevational view thereof, the left side being similar in appearance;

FIG. 3 is a top view;

FIG. 4 is a front elevational view; and
FIG. 5 is a rear elevational view.

I claim:

The ornamental design for a typewriter, substantially as shown and described.
